DESIGN FOR A SPOON OR OTHER ARTICLE
OF FLATWARE

Gilbert L. Crowell, Jr., deceased, late of Meriden, Conn., by Anna W. Crowell, executrix, Kearny, N. J., assignor to International Silver Company, Meriden, Conn., a corporation of New Jersey

Application September 22, 1933. Serial No. 49,319

Term of patent 14 years

To all whom it may concern:

Be it known that GILBERT L. CROWELL, JR., deceased, late a citizen of the United States, and a resident of Meriden, county of New Haven, State of Connecticut, invented a new, original, and ornamental Design for a Spoon or Other Article of Flatware, of which the following is a specification, reference being had to the accompanying drawing, forming a part thereof:

Fig. 1 is a front elevation of a spoon showing his new design; and

Fig. 2 is a sectional view on line 2—2 of Fig. 1. The back of the spoon conforms with the disclosure of Fig. 2, and may be plain or have surface ornamentation embodying the motif disclosed in Fig. 1.

The design is intended for use on sets comprising spoons, forks, knives and similar articles of tableware.

The following is claimed:

The ornamental design for a spoon or other article of flatware, substantially as shown and described.

ANNA W. CROWELL,
Executrix of the Estate of Gilbert L. Crowell, Jr., Deceased.
